UNITED STATES PATENT OFFICE.

JOHN E. DOWDEN, OF LAKE PRESTON, SOUTH DAKOTA.

MOLD FOR THE MANUFACTURE OF CONCRETE FENCE-POSTS.

1,293,731.

Specification of Letters Patent. Patented Feb. 11, 1919.

Application filed June 20, 1917. Serial No. 175,771.

To all whom it may concern:

Be it known that I, JOHN E. DOWDEN, a citizen of the United States, and resident of Lake Preston, in the county of Kingsbury 5 and State of South Dakota, have invented a certain new and useful Mold for the Manufacture of Concrete Fence-Posts, of which the following is the specification.

The object of my invention is to provide 10 a fence post mold of simple, durable and inexpensive construction.

A further object of my invention is to provide a mold so constructed and arranged that a plurality of posts may be made at the 15 same time from a single pouring of concrete.

A further object of my invention is to provide an improved collapsible mold adapted to form a plurality of concrete fence posts, which may be readily taken apart to remove 20 the post, when they have hardened and which is so constructed that it may be used under varying conditions such as for instance as using it with a cement sidewalk or other smooth surface for a pallet.

With these and other objects in view, my 25 invention further consists in the construction, arrangement and combination of the various parts of the device whereby the objects contemplated are attained as herein- 30 after more fully set forth, pointed out in my claims and illustrated in the accompanying drawings, in which:

Figure 1 shows a perspective view of my improved collapsible mold having parts 35 broken away to better illustrate the construction.

Fig. 2 shows a side elevation thereof.

Fig. 3 shows a side elevation of a completed post formed by the use of my 40 improved mold, and

Fig. 4 shows a detailed perspective view of parts of my device illustrating means for manufacturing posts of a particular shape.

Referring to the accompanying drawings, 45 I have used the reference numeral 10 to indicate generally a pallet upon which a plurality of boards 11 of equal size are placed on edge. The boards 11 are spaced relative to each other and the space between each 50 pair of the boards 11 is adapted to receive the concrete to form one post. Each of the boards 11 with the exception of the outer two is provided at the upper and lower edges of their sides with laterally projecting 55 strips 12 adapted to form a beveled or any other desired configuration on the corners of

the completed post. The outer members 11 are provided with similar strips 12 on their inner sides but not on their outer sides. The ends of the spaces between the members 11 60 are closed by means of end pieces consisting of boards 13 having a plurality of blocks 14 mounted on their inner surfaces. The blocks 14 and the boards 13 are each of the same width as the members 11 and the blocks 65 14 are of such length and so spaced from each other that the ends of each member 11 will be snugly received between a pair of blocks 14 thereby forming mortise joints 70 between the boards 11 and the end pieces. 75 The strips 12 have their ends cut the same distance from the ends of the boards 11 as the blocks 14 are wide, so that when the boards 11 are received between the blocks 14, the ends of the strips 12 will abut against 80 the blocks 14 thereby increasing the strength of the union between the boards 11 and the end pieces and also limiting the tendency of the assembled mold to buckle. The boards 13 are of such length that when all of the 85 boards 11 are received within their proper notches, the ends of the board 13 will project beyond the outer boards 11. Fixed to this projecting end of the member 13 at the side adjacent to the boards 11 are triangular blocks 15, which are so arranged that the end 90 of the outer boards 11 will be received within the notch formed between such block 15 and the adjacent block 14. The block 15 extends a sufficient distance along the outer 95 side of the outer member 11 so that buckling of the frame is further limited. A strip of resilient sheet metal 16 is secured to the outer members 11 by means of bolts or screws 17 adjacent to each block 15 and extends along the block 15 past the edge of the member 13 where it is bent to form a hook 18 having a handle member 19 formed at the end thereof. The member 16 is so shaped that the corner of the block 15 will 100 be tightly received between said member 16 and the adjacent side of the outer member 11 and also has the hook portion 18 so arranged that it will continually exert yielding pressure tending to hold the member 11 into the mortise between block 15 and the adjacent block 14 when the hook is in engagement with the member 13. At each end of the boards 11 a central pin 20 is placed, which projects through a suitably aligned 110 hole in the board 13 when the mold is assembled thereby tending to further limit

buckling of the mold and also insuring that the end member must be moved away from the boards 11 in such direction that there will be the least danger of the completed fence post becoming broken or having their corners chipped.

In the practical operation of my device, I produce fence posts 21 such as are shown in Fig. 3 having beveled corners 22. It will be understood that suitable forms may be secured to the blocks 14 so that the upper or lower ends of the post may be formed in any desired shape. Pattern molds may also be secured to the sides of the members 11; should it be so desired. In fact it will be understood that any desired shape of fence post may be made by means of my improved multiple fence post form, provided only that the mold required to make the desired pattern may be removed from the post by moving it directly away from the adjacent surface of the post. It will also be understood that the size of my device may be varied to suit the size of the post desired and that practically any number of posts may be made at the same time by merely adding to the length of the end members and increasing the number of the side members. Assuming that it is desired to make the greatest possible number of posts of the type, which would be produced by the mold shown in Fig. 1 of the drawings, the members would be assembled as shown in Fig. 1 and either placed upon a pallet such as is shown at 10 in Fig. 2 or placed on any convenient, smooth surface. Posts have been made with the use of this mold by using an ordinary cement sidewalk instead of the pallet. Assuming that the mold has been placed upon the pallet and the concrete mixed, the concrete is then poured into the mold until each of the spaces between the boards 11 is completely filled. The form may then be allowed to remain in place until the concrete has hardened so that it is desired to remove the mold therefrom. The first step in the latter operation is to move the hooks 18 at one end out of operative relation with the boards 13 and then tap the surface of the member 13 with a hammer or mallet until the particles of concrete have been loosened therefrom. The entire end member may be then slid outwardly away from the ends of the finished post on the pins 20. When the end member slides off the pins 20, it may be laid to one side and a similar operation performed with the second end member. In most cases, the removal of the end members leaves the balance of the boards unconnected as the drying of the concrete during its setting ordinarily separates the posts from the adjacent mold so that the mold boards may be moved without any difficulty. If, however, a post should stick to a mold, a very slight

tapping of the mold is usually sufficient to jar it loose from the particles of concrete, which are stuck to it. In Fig. 4 of the drawings, I have shown a means for making fence posts adapted for use at the corners of a field or lot whereby the post may be made of greater strength than are the posts between the corners and whereby the corner post may be provided with the laterally extending lug or projection for the purpose of securing braces thereto.

It will be understood that the corner posts of a fence are subject to much greater strain than are the other posts as the wire extends away from them in two directions, which are at right angles to each other. For this reason inclined brace rods are usually run from both the adjacent post to the upper part of the corner post thereby preventing it from being broken or moved from a vertical position. In order to secure these inclined braces to the corner post some means are necessary to prevent the ends of these braces from moving up and down relative to the posts. For this reason it is customary to provide laterally extending lugs or projections on the corner post. In order to adapt my form to make corner fence posts of sufficient strength but having the necessary lateral lugs, I provide an auxiliary form consisting of a base board 23, which is secured to a hollow rectangular form 24. The inside of the rectangular form 24 is adapted to form the lateral lug when the concrete is poured into the mold and the base board 23 forms a support, which may rest upon the boards 11. It also makes my corner posts of greater size and strength than are the other posts used in a fence and to accomplish this result omit one of the boards 11 thereby making the corner posts twice as wide as are the other posts of the fence. If it is desired that the top end of the post be smooth the groove between the blocks 14, which receives the board 11, may be filled by a suitable strip of wood or other material. The base board 23 is adapted to be detachably secured to the boards 11 by means of holes 25, which extend clear through the boards 11 and receive pins 26 when the base 23 is mounted on the form. By the use of holes 25, which extend clear through the boards 11, it will be seen that when the mold is used for making ordinary sized posts without the use of the lateral lug forming mold there is no necessity for guarding the holes 25 to prevent them from filling with concrete. In practice, it has been found that by extending the holes 25 clear through the boards, it is very easy to use the long spike to knock out any concrete, which may have lodged therein when it is desired to insert the pins 26 in the holes.

It will be seen from the foregoing that

my improved collapsible mold is especially adapted for the building of fence posts on account of its few and simple parts and because of the ease with which it may be operated. It will be seen from the foregoing description that I have provided three separate means for preventing the buckling of the assembled mold so that there is practically no danger of the posts being made crooked. The first of these devices consists of the mortise joints between the blocks 14, the strips 12 and the boards 11, the second device consists of the pins 20 with their coöperating openings in the board 13 and the third device consists of the blocks 15, which coöperate with the resilient members 16 to form a rigid joint. By the use of my improved mold, a large number of fence posts may be made within a very short time and with the use of but a very small amount of material for forms. The use of this collapsible form further does away with the large amount of waste of lumber where temporary forms are nailed or otherwise secured together in the ordinary manner.

I claim as my invention:

1. In a mold for fence posts, a pair of end members having a series of spaced, vertical grooves, each of said end members having near its ends blocks projecting laterally toward the opposite end member having beveled outer surfaces, the inner surface of each

block forming part of one of said grooves, a plurality of partitions and side members having their ends received in said grooves, 35 the outer side members having secured thereto spring clip devices extending along side the beveled face of said blocks and having at their outer ends hook members adapted to overlap and engage the ends of said end members, and handle members projecting beyond said hook members.

2. In a mold for fence posts, a pair of end members having a series of spaced, vertical grooves, each of said end members having near its ends blocks projecting laterally toward the opposite end member having beveled outer surfaces, the inner surface of each block forming part of one of said grooves, 40 a plurality of partitions and side members having their ends received in said grooves, the outer side members having secured thereto spring clip devices extending along side the beveled face of said blocks and having 45 at their outer ends hook members adapted to overlap and engage the ends of said end members, handle members projecting beyond 50 said hook members, and means for preventing vertical movement of the end members 55 with relation to said other members when the mold is assembled.

Des Moines, Iowa, May 29, 1917.

JOHN E. DOWDEN.
